Patented Feb. 13, 1912.

UNITED STATES PATENT OFFICE.

ELIJAH BUCK, OF MARSHALL, MICHIGAN.

SANITARY CUSPIDOR.

1,017,203.

Specification of Letters Patent.

Patented Feb. 13, 1912.

Application filed January 28, 1911. Serial No. 605,314.

To all whom it may concern:

Be it known that I, ELIJAH BUCK, citizen of the United States, residing at Marshall, in the county of Calhoun and State of Michigan, have invented certain new and useful Improvements in Sanitary Cuspidors, of which the following is a specification.

This invention has reference to an improved cuspidor, and has for an object to 10 provide an economical and simply formed device which may be discarded and replaced by a new article at short intervals so as to provide a sanitary device.

Another object of this invention is to form 15 an article of this character in such a manner that it may be made from paper, or other common substance, and wherein the cuspidor is fire-proof, by reason of a coating of fire-proof substance within the bowl of the same, 20 to protect the cuspidor when burning matches, cigarettes, or the like are thrown thereto. The fire-proof coating is also adapted to protect the paper or substance, from which the cuspidor is formed, from 25 moisture.

For a full understanding of the invention and the merits thereof and also to acquire a knowledge of the details of construction, reference is to be had to the following description and accompanying drawings, in 30 which:

Figure 1 is a perspective view of the improved cuspidor; Fig. 2 is a vertical central section taken through the same; Fig. 3 is a 35 plan view of the blank or strip from which the bowl is formed; Fig. 4 is a plan view of the strip or blank from which the base section is formed; and, Fig. 5 is a plan view of the bottom of the bowl.

40 Corresponding and like parts are referred to in the following description and indicated in all the views of the drawing by the same reference characters.

Referring to the drawing the improved 45 cuspidor comprises a base section, and a bowl. The base section is formed from an arcuate strip 10 of paper or the like which is relatively narrow and provided at one end with a tongue 11 adapted to engage through 50 a slit 12 formed at the opposite end of the strip 10 in setting up the base. It will be noted from Fig. 1 that the tongue 11, and

the adjacent end of the strip 10 are lapped over against the outer side of the opposite end of the strip, and that the tongue 11 is inserted inwardly through the slit 12.

The bowl of the cuspidor is formed from an arcuate strip 13 of considerable width and is provided at one edge with a number of tongues 14 spaced apart and adapted for 60 engagement in a corresponding number of slits 15 which are formed in the opposite end of the strip 13. In a like manner the tongues 14 and the adjacent end of the strip 13 overlap against the outer face of the opposite end of the strip 13, the tongues 14 extending in through the slits 15. The inner edge of the strip 13 is slotted radially to provide a number of flaps 16 adapted to be folded up under against a circular bottom 70 65 17 fitted within the bowl.

When the base strip 10 is bent into circular form the tongue 11 is inserted through the slit 12 and secured therein, preferably by an adhesive substance, although any other 75 suitable means may be employed. The base portion assumes a frusto-conical shape and is adapted to have its enlarged lower end seat upon the floor and to present its upper reduced end for the reception of the bowl. 80

The bowl is formed by bending the strip 13 into circular form, passing the tongues 14 through the slits 15 and securing the same in any suitable manner, as by an adhesive substance. The bottom 17 is now inserted 85 through the enlarged open end of the bowl and pressed down into the reduced end thereof, the flaps 16 being turned up against the under side of the bottom and secured thereto by adhesive substance. The inner 90 side of the strip 13, and the bottom 17 are provided with a coating 18 of fire proof material, which is also impervious to moisture. The bowl, now formed, is loosely fitted in the upper reduced end of the base strip 10 95 by means of which it is supported in an upright position.

It is readily seen that this improved cuspidor can be made of paper, or the like and that it is of very simple form so that it can 10 be economically produced and may be thrown away after slight usage and renewed with but slight expenditure.

The lining or coating within the bowl 13
